H. RUE

BUTT EXTINGUISHER AND TRAY

Filed Nov. 21, 1927

FIG. 1.

FIG. 3.

INVENTOR,

Hans Rue;
by F. Maynard, ATTORNEY.

UNITED STATES PATENT OFFICE.

HANS RUE, OF LOS ANGELES, CALIFORNIA.

BUTT EXTINGUISHER AND TRAY.

Application filed November 21, 1927. Serial No. 234,688.

This invention relates to smokers' supplies and especially to a safety cigar and cigarette butt and ash tray, and fire extinguisher.

The extensive use of automobiles has led to a great influx of a careless and reckless class of people into the unprotected country and mountain districts where, because of the amount of inflammable grass and brush, many fires are caused by off-cast burning cigars, cigarettes and matches.

This condition has resulted in the enforcement of "no smoking" restrictions in the hazardous country and in laws against casting of burning cigars, etc. along highways.

This presents a need for a simple, practicable and low cost and safe means for receiving these smokers' stubs and matches and ashes.

Therefore an object of this invention is to provide a device which may be readily attached to a convenient part of an automobile and serve to hold lighted cigars and cigarettes; to extinguish them, and to receive and contain the waste butts and match stems until they may be safely discarded.

The device is not confined to use only as autoists' equipment but may be arranged on any convenient support in the home, office, club or other place frequented by smokers.

There are other objects, advantages and features of construction as will be made manifest in the following description of the herewith illustrative embodiment; it being understood that modifications and adaptations may be resorted to within the spirit, scope and principle of the invention as it is more directly hereinafter claimed.

Figure 1 is a perspective of the device as applied to a wind shield, by a suction cup.

Figure 2 is a longitudinal section of the device showing a cigarette disposed in fire extinguishing position.

Figure 3 is a cross-section; the barrel in inverted dumping position over the tray drawer.

Figure 4 is a cross-section showing the temporary clamping of a cigarette end by the barrel lip.

The device includes a generally oblong box or housing 2 one end of which is open for the insertion and withdrawal of a complementary drawer 3 having an end knob 4.

The drawer 3 has a cross partition 5 forming an ash pit in the outer end and in a position remote from the opposite end of the box and at which is a match pocket 6.

The box 2 is substantially closed at its upper part by a top 7 which has a longitudinal, cylindrical ridge 8 provided with an open top mouth 9 and a throat 10 directly below.

Snugly and turnably fitting in the ridge cylinder 8 is a barrel 11 having along one side an orifice 12 to register with the mouth 8 and when the barrel is reversed the orifice registers with the throat 9 and will discharge its contents into the subjacent drawer 3.

For the purpose of extinguishing the fire of cigars and cigarettes before they are laid in the open barrel there is provided in one end of the barrel a sliding pincer in the form of a plunger 15 having a stem 16 sliding and rotative in an end bearing 17 on the end of the shell cylinder 8. The pincer 15 is not turnable in the barrel and it is pressed outward by a spring 18 enclosed in a thimble 19 on the stem 16. The inner end of the pincer is recessed and when pressed on the thimble 19 will crush the burning end of a cigarette C against an abutment 20 fixed in the barrel. Ashes from the quenched fire will pass through a hole 21 in the bottom of the barrel and fall into the ash pit in the drawer. Continued inward movement of the pincer will topple the cigarette over into the barrel 11.

A funnel wall 22 forms a guide to place the cigarette in register with the pincer 15 and the abutment 20.

The open pincer and the wall 20 will form a holder for a cigarette disposed therein to be removed at will without pinching out the fire.

When the barrel is to be emptied this is accomplished simply by turning the thimble and its attached pincer 15, which results in rotating the receiving barrel a half turn to emptying position.

The box may be provided with a suction cup 25 at the back so that it can be adhered to glass or on any smooth surface or it may have a wedge part 26 for application to a socket piece 27 which may be secured to any desired part, as the frame in the tonneau of an automobile.

It is understood that various advertising matter may be applied to one or more of the different panels of the device.

What is claimed is:

- 5 1. A safety smokers' ash and butt tray including a box having a drawer removable from the box, a cylinder forming the box top and having a top mouth and a throat leading into the box, and a barrel turnably 10 fitting in the cylinder and having an orifice along one side to register with the mouth for admission of stubs into the barrel interior; said barrel in reversed position closely closing the said mouth and a sliding butt pincer 15 in the barrel.
2. A safety ash and butt tray including a box, a drawer in the box, having an ash pit and a separate butt chamber, a rotary barrel closing the top of the chamber and having a 20 receiving orifice along the top and an outlet into said pit at the bottom, and means for

quenching butt fire and toppling the butt into the barrel.

3. A safety ash and butt tray including a box, a drawer therein, a barrel closing the 25 top of the box and having a receiving slot along its top, and means in the barrel for quenching the fire of an inserted butt and toppling the butt into the barrel said means operative to rotate the barrel to discharge its 30 contents into the drawer.

4. A safety ash and butt tray including a box, a drawer therein, a barrel closing the top of the box and having a receiving slot along its top, and means in the barrel for 35 quenching fire of an inserted butt and toppling the butt into the barrel said means operative to rotate the barrel to discharge its contents into the drawer; said drawer having an ash pit below said quenching means.

HANS RUE.
